PINWHEEL TOY

Ronald A. Ringenback, Shelton, Conn. (18 Capitol Drive, Huntington, Conn.), assignor of one-half to Daniel J. O'Connor, Jr., Stratford, Conn.

Filed Mar. 26, 1964, Ser. No. 79,200

Term of patent 14 years

(Cl. D34—15)

FIG. 1 is a front elevation of a pinwheel toy showing my new design;

FIG. 2 is a side elevation;

FIG. 3 is a top plan view; and

FIG. 4 is a perspective view.

I claim:

The ornamental design for a pinwheel toy, substantially as shown.
